United States Patent Office

Des. 201,766
Patented July 27, 1965

201,766

STAMP DISPENSER

George J. Perkins, 44 Hawthorne Road, Barrington, Ill.

Filed Feb. 5, 1964, Ser. No. 78,528

Term of patent 14 years

(Cl. D52—2)

Fig. 1.

Fig. 6.

Fig. 2.

Fig. 3.

Fig. 4

Fig. 5.

FIG. 1 is a right side perspective view of a stamp dispenser showing my new design;

FIG. 2 is a side elevational view of the stamp dispenser showing the same side that is shown in FIG. 1 with the side opposite being identical with the side that is shown; FIG. 1;

FIG. 3 is a rear elevational view of the stamp dispenser of FIG. 1;

FIG. 4 is a top plan view of the stamp dispenser of FIG. 1;

FIG. 5 is a bottom plan view of the stamp dispenser of FIG. 1;

FIG. 6 is a reduced side elevational view of a modified form of the stamp dispenser and corresponds to the illustration of FIG. 2, with the side opposite the side shown being identical therewith.

I claim:

The ornamental design for a stamp dispenser, substantially as shown and described.
